United States Patent Office

Des. 219,000
Patented Oct. 20, 1970

219,000

TABLE KNIFE

Jose Carlos Mario Bornancini, Porto Alegre, Brazil, assignor to Hercules S.A.-Fabrica de Talheres, Rio Grande do Sul, Brazil, a corporation of Brazil

Filed July 10, 1969, Ser. No. 18,164

Term of patent 14 years

Int. Cl. D7—03

U.S. Cl. D95—3

In the drawings:

FIG. 1 is a side view of a table knife showing my new design;

FIG. 2 is a back edge view of the table knife;

FIG. 3 is a side view opposite that shown in FIG. 1;

FIG. 4 is a section taken on the line 4—4 of FIG. 1;

and

FIG. 5 is a section taken on the line 5—5 of FIG. 1.

I claim:

The ornamental design for a table knife, as shown.
